Inventor

BURRIS E HAYES

By *Burris E Hayes*
Attorney

UNITED STATES PATENT OFFICE.

BURRIS E. HAYES, OF CORYDON, IOWA.

ATTACHMENT FOR PLOWS.

Application filed July 8, 1921. Serial No. 483,562.

To all whom it may concern:

Be it known that I, BURRIS E. HAYES, a citizen of the United States, residing at Corydon, in the county of Wayne and State 5 of Iowa, have invented certain new and useful Improvements in Attachments for Plows, of which the following is a specification.

This invention relates to improvements in plows and the object is to provide a simple, practical and efficient device for preventing the accumulation of rubbish such as old straw, old stalks or weeds in front of the colter of the plow when plowing land containing the same. This difficulty is found particularly troublesome when it is attempted to run a plow through old straw stack bottoms, as the straw quickly bunches up in front of the colter, making further progress 10 impossible without first removing the bunches and lifting the plow up until clear ground is again reached. The invention is more particularly described in the following specification and is clearly illustrated in the 15 accompanying drawing, in which:

Fig. 1 is a side elevation of a gang plow, the right supporting wheel and other minor parts being omitted.

Fig. 2 is a plan view of the plow beam 20 frame, showing the positions of the plows and colters relative to the parts embodying my improvement.

Fig. 3 is a fractional detail view showing a modification of the invention.

Referring to the drawing by reference characters A designates a plow frame or carriage supported on wheels B and to which is secured a pair of plows C and corresponding colters, all of common and well known construction. To the front part of the frame A (or to the forward end of each of the plow beams comprising the frame) I secure as at E a rearwardly inclined bar F, one for each colter. The rear ends of the bars F extend 35 back to within a short distance of the colters D and at a height substantially on a level with the colter centers. The bars are supported at said rear ends by brackets G which are bolted at their upper ends as at H to the 40 plow beams, while their lower ends have angular projections J adapted to be bolted as at K to the bars F. In the event that the rear end of either of the bars F should need to be adjusted in order to bring it directly in 45 front of the colter it is found desirable to

first loosen the bolt K, then twist the lower part of the bracket G slightly one way or the other. This will swing the projection J until the bar F is in the right position when the bolt K may again be tightened. In the 60 modification shown in Fig. 3 this adjustment is made easier, as here the shank of the bracket G is round and is held in a socket L secured to the plow beam by bolts M, and by merely loosening said socket and the bolt K, 65 the bar F can be adjusted to and secured in any position found necessary.

It will be obvious with this construction in operation that the bar F will positively prevent the accumulation and bunching up of 70 old straw or other matter in front of the colters, as all such matter will be gradually pressed down to the plowing level before being engaged by either the colters or the 75 plows.

It is understood that suitable modifications may be made in the form and structure of this invention and in the mode of applying it to plows of various makes and types, provided however that such modifications 80 come within the spirit and scope of the appended claims.

Having now therefore fully shown and described my invention, what I claim to be new and desire to protect by United States 85 Letters Patent is:

1. In combination with a plow beam having a plow and a colter secured thereunder, a rearwardly inclined bar secured at its front end to the plow beam and extending down to 90 the colter at its rear end, a substantially vertical bracket secured at its upper end to the plow beam so as to be rotatable relative thereto when so desired, an angular extension at the lower end of the bracket and a bolt 95 adapted to secure said extension to the rear part of the bar, as set forth and described.

2. In combination with a plow beam having a plow and a colter secured thereunder, a rearwardly inclined bar secured at its front end to the plow beam and extending down to 100 the colter at its rear end, a substantially vertical bracket having its upper end round and secured in a socket on the plow beam so as to be rotatable when so desired, an angular extension at the lower end of the bracket and a bolt 105 adapted to secure said extension to the rear part of the bar.

In testimony whereof I affix my signature.
BURRIS E. HAYES.
